UNITED STATES PATENT OFFICE.

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT.

GEARING.

1,040,502.

Specification of Letters Patent.

Patented Oct. 8, 1912.

Application filed July 3, 1912. Serial No. 707,437.

To all whom it may concern:

Be it known that I, ROBERT S. BROWN, a citizen of the United States, residing at New Britain, in the county of Hartford and 5 State of Connecticut, have invented certain new and useful Improvements in Gearing, of which the following is a specification.

This invention relates to gearing, one of the primary purposes of the invention being 10 to provide effective means whereby a part such as a shaft, can be operated either by power or hand, the construction being such that the two operating means cannot be simultaneously in action.

15 In the drawings accompanying and forming part of the present specification I have shown in detail one of the several convenient forms of embodiment of the invention which to enable those skilled in the art to 20 practice the same will be set forth fully in the following description. I do not restrict myself, however, to such disclosure; I may depart therefrom in several respects within 25 the scope of the invention defined by the claims following said description.

Referring to said drawings: Figure 1 is a side elevation of a metal working machine involving my invention, and, Fig. 2 is a horizontal section on the line 2—2 of Fig. 30 1 looking in the direction of the arrow.

Like characters refer to like parts in both views.

My improvements can be incorporated with utility in various kinds of metal working machines, and in fact machines of other types, the invention not being limited in this respect. In Figs. 1 and 2 of the drawings I have shown certain of the members of a multiple-spindle automatic turret-machine such as shown in Letters Patent No. 874,035 of December 17, 1905 granted to George G. Prentice to which reference may be had. A machine such as that shown in said Letters Patent includes in its organization a base or bed as 5 constituting part of the framework and which sustains certain of the moving parts among which is the shaft 6 generally known as the "cam shaft". It is one of the objects of the present invention 45 to effect the movement of this shaft either by power or hand, the relation being such as will hereinafter appear, that both operating mechanisms cannot be in use at the same time. This cam shaft is provided with the 50 adjuncts shown in said Letters Patent and

which need not, therefore, be described, as the same in themselves constitute no part of the present invention. I have shown as rising from the bed 5 the bearings 7 and 8 usually integral therewith and tied together 60 by the brace 9. This portion of the showing, however, constitutes the subject matter of a separate copending application filed July 5, 1912, Serial No. 707,658. The bearings 7 and 8 support the spindles 10. It is 65 needless for me to further describe this part of the machine, the same being set forth in detail in said other application.

The bed 5 is shown provided upon one side thereof with a power operable shaft 11 70 which may receive its motion in any desirable manner, for instance by a train of gears operated from some suitable source of power, the terminal one thereof being shown and being designated by 12. In axial coincidence with the shaft 11 is a second shaft 13 also supported by a bearing on the bed 5, the shaft 13 having a reduced end fitting a socket in the shaft 11. Through clutch means I can connect or disconnect the shaft 80 11 and the shaft 13, and it will be apparent that when these two shafts are connected the shaft 13 will be rotated provided the shaft 11 is being turned, and when they are disconnected the shaft 13 will be thrown 85 out of action. The clutch means shown for putting the two shafts into and out of operative relation will be hereinafter described. The cam shaft 6 receives its motion from the shaft 13 through suitable 90 means, for instance such as those now to be described. Said shaft 13 at its inner end has fastened thereto a bevel gear 14 in mesh with a substantially similar bevel gear 15 and the transverse shaft 16 supported by 95 suitable bearings upon the head end of the bed 5. Said shaft 16 between its ends is equipped with a worm 17 in mesh with the worm gear 18 fastened to the cam shaft 6. It will, therefore, be clear that when the 100 shaft 16 is turned the cam shaft 6 will be operated a similar extent. The said shaft 16 as already described is adapted to be operated by power. It may also as will hereinafter appear be operated by hand, and 105 hand operating means are such as to adjust the said shaft 6, so that parts which receive their motion therefrom can be correspondingly adjusted.

The bevel gear 15 is shown located at one 110

end of the shaft 16. Said shaft has fastened to its opposite end the spiral gear 19 in mesh with a substantially similar spiral gear 20 on the shaft 21 supported by a bearing on the bed on the side opposite to that carrying the shafts 11 and 13. In axial alignment with the shaft 21 is a shaft 22 adapted as will hereinafter be set forth to be manually operated and which through clutch mechanism as will hereinafter appear is adapted to turn the shaft 21 and therefore through the connections already described, adjust the cam shaft 6. The bed 5 is equipped with a suitable bearing for sustaining the shaft 22 and said shaft fits a socket in the coöperating shaft 21. Owing to the described connection between the two sets of shafts they are effectively supported at their ends presenting in effect, except so far as their motion is concerned, continuous shafts.

Splined to the shaft 11 for rotative movement therewith and longitudinal movement thereon, is a clutch member 23 coöperative with the clutch member 24 fastened to the shaft 13. It will be clear that when the clutch member 23 engages the clutch member 24, the two shafts 11 and 13 will be operatively connected together, so that if the shaft 11 be turned, the cam shaft 6 through the intermediate parts already described will be rotated by power.

Splined to the shaft 21 for rotation therewith and for longitudinal movement thereon is the clutch member 25 coöperative with the clutch member 26 fastened to the shaft 22. It will be evident that when the clutch members 25 and 26 are connected together and that when the shaft 22 is turned by hand, the cam shaft 6 through the intervening connections already set forth, can be rotated. The two clutches the halves or sections of which have already been described are so related that the shiftable members thereof cannot be simultaneously advanced. That is to say when the clutch member 23 is advanced the clutch member 25 will be retracted and vice versa, so that the halves of the clutches cannot be engaged at the same time.

There is shown supported by bearings on the under side of the bed 5 the rock shaft 27 provided at its ends with forks 28 and 29 straddling the clutch halves or members 23 and 25 respectively, and the branches of which are provided with pins or studs entering peripheral grooves or channels in said respective clutch halves after the well-known manner in clutch shifting devices. The two forks 28 and 29 and the shaft 27 are so related that when said shaft is rocked in one direction one clutch member such as the member 23 will be advanced to engage the companion clutch member 24, while the companion clutch member will be retracted to

thereby disengage it from the coöperating clutch member 26. To facilitate the operation of the clutch member shifting devices one of the forks as that denoted by 29 may be provided with an upwardly extending portion 30 terminating in a handle 31 which can be grasped by the attendant to simultaneously operate the clutch members 23 and 25. It will be assumed that the clutch member 23 is disengaged from the clutch member 24 and that the clutch members 25 and 26 are in engagement so that the cam shaft 6 can be operated by hand but not by power, notwithstanding the fact that the shaft 11 may be rotating. To facilitate the operation of the shaft 22 the hand crank 32 may be provided, said hand crank being adapted through suitable interposed gearing to transfer its effect to the shaft 22 for rotating the same when occasion therefor is required. The said hand crank 32 is fastened to the shaft 33 rotatively supported by the arm 34 on the bearing for the shaft 22. Fastened to said shaft 33 is a spiral gear 35 in mesh with a similar spiral gear 36 on the shaft 22. Therefore, when the clutch members 25 and 26 are engaged the shaft 6 can be manually adjusted by turning the hand crank 32, the effect of the latter being applied to the shaft 22 through the interposed described gears and the motion of said shaft 22 being transferred to the cam shaft through the agency of the connections already described.

What I claim is:

1. In a machine of the class described, the combination of a power operable shaft, a second shaft coaxial therewith, a clutch for clutching and unclutching said power operable and said coaxial shaft and comprising a movable member, a manually operable shaft, a fourth shaft coaxial with said manually operable shaft, a clutch for clutching and unclutching said manually operable shaft and the shaft coaxial therewith and also comprising a movable member, a fifth shaft, driving connections between said second and fourth shafts and said fifth shaft, and mechanism for advancing the movable member of one clutch and for simultaneously retracting the movable member of the other clutch and vice versa.

2. In a machine of the class described, the combination of a power operable shaft, a second shaft coaxial therewith, a clutch for clutching and unclutching said power operable and said coaxial shaft and comprising a movable member, a manually operable shaft, a fourth shaft coaxial with said manually operable shaft, a clutch for clutching and unclutching said manually operable shaft and the shaft coaxial therewith and also comprising a movable member, a fifth shaft, driving connections between said second and fourth shafts and said fifth shaft, and a rock shaft provided with forks connected with

the movable members of the respective
clutches and adapted when turned in one
direction to advance one of said movable
members and to simultaneously retract the
5 other movable member and adapted when
turned in the opposite direction to reverse
said operation.

3. In a machine of the class described, the
combination of a bed, a cam shaft extending
10 longitudinally of said bed, a second shaft
extending transversely of the bed and opera-
tively connected with the cam shaft for ro-
tating the same, a third shaft and a fourth
15 shaft both operatively connected with said
transversely extending shaft, a power oper-
able shaft coaxial with the third shaft, a

manually operable shaft coaxial with the
fourth shaft, a clutch between the power op-
erable shaft and the third shaft, a second
clutch between the manually operable shaft 20
and the fourth shaft, each of said clutches
comprising a movable member, and mecha-
nism for advancing one of the movable
clutch members and for simultaneously re-
tracting the other movable clutch member 25
and for also reversing said operation.

In testimony whereof I affix my signature
in presence of two witnesses.

ROBERT S. BROWN.
